UNITED STATES PATENT OFFICE.

HENRY KÜNTZLER, OF WILKES-BARRE, PENNSYLVANIA, ASSIGNOR, BY MESNE ASSIGNMENTS, TO ADDER MACHINE COMPANY, A CORPORATION OF PENNSYLVANIA.

FLEXIBLE DRAFT CONNECTION FOR ADDING-MACHINES.

1,080,516.

Specification of Letters Patent.

Patented Dec. 2, 1913.

Application filed January 19, 1909. Serial No. 473,041.

To all whom it may concern:

Be it known that I, HENRY KÜNTZLER, a citizen of the United States, and resident of Wilkes-Barre, Luzerne County, Pennsylvania, have invented certain new and useful Improvements in Flexible Draft Connections for Adding-Machines, of which the following is a specification.

This invention relates to the operating mechanism of adding machines, and similar mechanisms, and its novelty consists in the construction and adaptation of the parts, as hereinafter pointed out. In a co-pending application for Letters Patent of the United States, Serial No. 472,701 filed on the 18th day of January, 1909, there is described an operating mechanism for such a machine comprising in brief a main shaft from which the mechanism of the adding machine is moved, an auxiliary rock shaft, an operating handle, a rigid connection between the handle and the auxiliary shaft, a flexible connection between the auxiliary shaft and the main shaft and means for automatically locking the auxiliary shaft, and consequently limiting its movement and that of the handle, at the end of the stroke of the handle, and before the main shaft has quite completed its stroke and means operated from the main shaft for unlocking the auxiliary shaft as the main shaft completes its stroke. In the mechanism described in that patent, the movements of the two shafts were not necessarily or actually in unison. In fact, the auxiliary shaft on the forward stroke was intended to be slightly ahead of the main shaft and the flexible connection between the two shafts, which was in the form of a draft spring, was always stretched considerably in the transmission of power. This form of device is useful where a fluid governor or similar controller is used to regulate the speed of the main shaft and is especially useful where the auxiliary shaft is actuated through a motor.

The mechanism which is the subject matter of the present application represents a state of the development of the mechanism intermediate that described in the application for a patent and the prior state of the art when a rigid connection existed between the handle and the main shaft of the machine.

This invention comprises, as before, a

main shaft, an auxiliary shaft and a flexible connection between them, but the flexible connection is made of a draft spring, or springs, of such strength that normally the main shaft moves in unison with the auxiliary shaft. There is also a lock but it does not operate except in an emergency when the strain on the draft spring is greater than a draft strain due to the accidental or other detention of the main shaft. Then the lock, which includes a detent, is brought into play and locks the auxiliary shaft against a reverse movement until the main shaft is released and is permitted to move forward when in so doing it actuates a releaser which moves the detent away from its engagement with the auxiliary shaft.

In the drawings, Figure 1 is a top plan view and partial section of a portion of an adding machine embodying the invention; Fig. 2 is a side elevation, and partial section of the same parts; Fig. 3 is a side elevation of the locking mechanism, the detent being in normal position; Fig. 4 is a side elevation of the parts shown in Fig. 3 showing the detent in the act of being released, and Fig. 5 is a side elevation of the same parts showing the detent holding the auxiliary shaft locked.

In the drawings, 1 is the base of the machine and 2 is one of the side frames, of which there are two, one on each side of the machine.

3 is the main shaft of the machine supported in suitable bearings.

Secured rigidly to the main shaft in any suitable manner is a bracket 30 to which by a pivot 300 is fastened a link 31 to which is secured a draft spring 32, secured at its opposite end to a link 33 fastened by a pivot 330 to a bracket 34 secured in turn to an auxiliary shaft 35 mounted in bearings in one of the side frames 2 and in a sub-frame 20 secured to the base 1 of the machine by bolts 21, or in any suitable manner. All of these parts are, in the construction shown, arranged in pairs in order that the work may be divided between the two draft springs which are then not required to be of unwieldy size. The two brackets 34 are separated by a spacing collar 36. To one end of the shaft 35 there is rigidly secured a crank 37 provided with a pivot 38 by which it is connected to a link 39, the other end of

which is secured by a pivot 301 to an oscillating member 302 serving as a crank and which is secured to a hollow shaft 303 adapted to be oscillated from a handle 304 through a hub 305 with which it is connected.

When the handle 304 is moved forward the hollow shaft 303 is oscillated. This motion is transmitted through the rigid link 39 10 to the crank 37 which oscillates the auxiliary shaft 35 to move the brackets 34 and through them the draft springs 32, brackets 30 and main shaft 3. It is obvious that if the draft springs 32 are strong enough to 15 transmit the motion referred to without stretching them the main shaft 3 is moved from the handle 304 substantially in the same manner as when the handle is secured directly to the main shaft itself.

20 Mounted to swing on a pivot 309 on the sub-frame 20 is a detent 310 to which is hinged a link 311 to the other end of which is secured a spring 312 whose other end is fastened to a permanent part of the machine. The detent 310 has a slot 365 adapted 25 to be engaged by a pin 366 projecting laterally from the sub-frame 20. On the end of the detent is mounted a roller 364, adapted to be supported upon the edge 363 of a snail back cam 360 secured to the auxiliary shaft 35 and provided with a shoulder 362.

30 Mounted to swing on a pivot 340 is a releaser arm 341 comprising a tip 342 adapted to contact with the latch arm 310 and a tail 343 upon which is pivoted a roller 344. A spring 345 secured to the arm 340 and a fixed part of the machine keeps a constant tension upon the tail 343. Secured to the main shaft 3 is a cam plate 346 having a convex surface 347 and a recessed or concave surface 348.

35 When the machine is normal, the springs 32 are of sufficient strength to transmit the motion of the auxiliary shaft 35 to the main shaft 3 so that they practically move in unison and the roller 364 is held against the edge 363 of the cam 360 by the tension of the spring 312, and moves idly back and forward thereon as the shaft 35 is oscillated. 40 But suppose that for any reason, for instance, a jam among the actuating devices of the adding machine, the main shaft 3 is detained. Then the auxiliary shaft 35 continues to move, stretches the spring 32 and 45 the roller 364 finally falls, or is pulled from the shoulder of the cam 360 and lodges against it, as shown in Fig. 5. It thus firmly locks the auxiliary shaft against any reverse movement under the influence of the main 50 spring of the adding machine, or other power transmitting mechanism, and the delicate devices in the machine are not injured by a sudden strain which they are not prepared to resist. Suppose, now that the 55 cause of detention of the main shaft is re-

70 moved, then as the cam 346 moves forward, the roller 344 on the releaser 341 reaches the recess 348 and under the influence of the spring 345, which is stronger than the spring 312, the releaser is tilted and its tip 342 contacts with the under edge of the detent 310 and lifts its roller 364 out of engagement with the shoulder 362 on the cam 360 and unlocks the auxiliary shaft as shown in Fig. 4. The pivot 366 and slot 365 serve to limit 75 the extent of movement of the detent 310.

75 The hub 305 of the handle 304 is provided with a notch or recess 370 (see Figs. 1 and 2) adapted to engage a tip 371 of a latch bar 372 placed within a hollow arm 373 projecting radially from the sleeve 303. The hollow arm is internally threaded and is adapted to receive a cap 374 provided with a recess 375 to receive the end of the latch bar 372. A spring 376 is adapted to surround the latch bar 372 and presses against the cap 374 and the rear 377 of the tip 371 normally moving the latter toward the hub 305. An aperture 378 is provided in the sleeve 303 to receive the tip 371.

80 The parts just described are normally in the position shown in Fig. 2. When the handle is rotated anti-clockwise the tip 371 is engaged by the notch 370 of the hub 305 and this hub 305 and the sleeve 303 move 85 together and the power is transmitted to the link 39. When the end of the stroke is reached the parts of the machine are returned through the agency of the main spring of the machine irrespective of the position of the handle and the latter is moved backward through the engagement of the latch bar 372 with the notch 370, but the handle may be moved backward without rotating the sleeve 303, because the hub 305 90 will, if rotated backward with respect to the sleeve 303, force the latch bar 372 inwardly against the tension of the spring 376 and will keep the latch bar 372 in that position until the hub 305 is rotated far enough to 95 allow its notch 370 to again engage the tip 371. This construction enables the handle to be quickly and readily removed and as easily inserted in place without the use of 100 screws, bolts or other fastening devices.

105 110 115 What I claim as new is:

1. In a mechanism of the character described, comprising an oscillatory main shaft, an oscillatory auxiliary shaft and a flexible connection between them adapted normally 120 to move the main shaft in unison with the auxiliary shaft when the latter is oscillated, means adapted to hold the auxiliary shaft against a reverse oscillation should the main shaft be detained, consisting of a rotating support on the main shaft, a detent normally resting inactive on said support, and a recess in said support whereby the detent 125 will fall into a locking position.

2. In a mechanism of the character de- 130

- scribed, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against a reverse oscillation should the main shaft be detained, consisting of a cam on the shaft, and a detent resting thereon in the normal operation of the machine, and adapted to engage therewith when the cam has rotated through a predetermined arc. 70
3. In a mechanism of the character described, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against a reverse oscillation should the main shaft be detained, consisting of a snail back cam on the shaft, a hinged detent supported thereon against the force of gravity and a tip adapted to engage the shoulder of the cam when the latter has rotated beyond a predetermined point. 75
4. In a mechanism of the character described comprising an oscillatory main shaft, an oscillatory auxiliary shaft and a flexible connection between them adapted normally to move the main shaft in unison with the auxiliary shaft when the latter is oscillated, means adapted to hold the auxiliary shaft against a reverse oscillation should the main shaft be detained, consisting of a snail back cam on the shaft, a hinged detent yieldingly held against the edge of the cam and adapted to engage its shoulder when the cam is rotated. 80
5. In a mechanism of the character described, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against the reverse oscillation should the main shaft be detained, consisting of a rotating support on the main shaft, a detent normally resting inactive on said support, and a recess in said support whereby the detent will fall into a locking position, and means adapted to limit the extent of the movement of the detent. 85
6. In a mechanism of the character described, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against the reverse oscillation should the main shaft be detained, consisting of a rotating support on the main shaft, a detent normally resting inactive on said support, and a recess in said support whereby the detent will fall into a locking position, and means adapted to limit the extent of the movement of the detent. 90
7. In a mechanism of the character described, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against a reverse oscillation should the main shaft be detained, consisting of a snail back cam on the shaft, a hinged detent adapted to contact with the edge of the cam, a spring adapted to maintain such contact and a shoulder on the cam with which the detent is adapted to engage. 95
8. In a mechanism of the character described, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against a reverse oscillation should the main shaft be detained, and a releasing device moved from the main shaft adapted to interrupt the function of the holding device when the main shaft ceases to be detained. 100
9. In a mechanism of the character described, comprising an oscillatory main shaft, an oscillatory auxiliary shaft and a flexible connection between them adapted normally to move the main shaft in unison with the auxiliary shaft when the latter is oscillated, means adapted to hold the auxiliary shaft against a reverse oscillation should the main shaft be detained, and a releasing device moved from the main shaft adapted to interrupt the function of the holding device when the main shaft ceases to be detained, consisting of a tiltable lever, means adapted normally to hold it away from the auxiliary shaft detaining means and means moved from the main shaft to tilt the lever against such means. 105
10. In a mechanism of the character described comprising an oscillatory main shaft, an oscillatory auxiliary shaft and a flexible connection between them adapted normally to move the main shaft in unison with the auxiliary shaft when the latter is oscillated, a movable detent adapted to hold the auxiliary shaft against a reverse oscillation until the main shaft ceases to move. 115
11. In a mechanism of the character described comprising an oscillatory main shaft, an oscillatory auxiliary shaft and a flexible connection between them adapted normally to move the main shaft in unison with the auxiliary shaft when the latter is oscillated, a movable detent adapted to hold the auxil- 120
12. In a mechanism of the character described comprising an oscillatory main shaft, an oscillatory auxiliary shaft and a flexible connection between them adapted normally to move the main shaft in unison with the auxiliary shaft when the latter is oscillated, a movable detent adapted to hold the auxil- 125
13. In a mechanism of the character described comprising an oscillatory main shaft, an oscillatory auxiliary shaft and a flexible connection between them adapted normally to move the main shaft in unison with the auxiliary shaft when the latter is oscillated, a movable detent adapted to hold the auxil- 130

- iary shaft against a reverse oscillation until the main shaft ceases to move, and a releasing device moved from the main shaft against said detent.
12. In a mechanism of the character described, comprising an oscillatory main shaft, an oscillatory auxiliary shaft and a flexible connection between them adapted normally to move the main shaft in unison with the auxiliary shaft when the latter is oscillated, a movable detent adapted to hold the auxiliary shaft against a reverse oscillation until the main shaft ceases to move, and a releasing device moved from the main shaft against said detent, consisting of a tiltable lever provided with a tip adapted to contact with the detent, a cam on the main shaft adapted normally to hold the lever out of such contact and provided with a recess into which a portion of the lever can be forced to permit such contact.
13. In a mechanism of the character described, comprising an oscillatory main shaft, an oscillatory auxiliary shaft and a flexible connection between them adapted normally to move the main shaft in unison with the auxiliary shaft when the latter is oscillated, a movable detent adapted to hold the auxiliary shaft against a reverse oscillation until the main shaft ceases to move, and a releasing device moved from the main shaft against said detent, consisting of a lever provided with a tip adapted to be moved against the detent and with a tail, a cam on the main shaft and a spring adapted normally to hold the tail against the cam.
14. In a mechanism of the character described, comprising an oscillatory main shaft, an oscillatory auxiliary shaft and a flexible connection between them adapted normally to move the main shaft in unison with the auxiliary shaft when the latter is oscillated, a detent adapted to detain the auxiliary shaft and a releaser adapted to interrupt the function of the detent.
15. In a mechanism of the character described, comprising an oscillatory main shaft, a cam mounted thereon, an oscillatory auxiliary shaft, a cam mounted thereon, and a flexible connection between the shafts adapted normally to move the main shaft in unison with the auxiliary shaft when the latter is oscillated, a detent adapted to detain the auxiliary shaft and a releaser adapted to interrupt the function of the detent, the detent being controlled by the cam on the auxiliary shaft and the releaser by the cam on the main shaft.
16. In a mechanism of the character described, comprising an oscillatory main shaft, a cam mounted thereon, an oscillatory

auxiliary shaft, a cam mounted thereon, and a flexible connection between the shafts adapted normally to move the main shaft in unison with the auxiliary shaft when the latter is oscillated, a detent adapted to detain the auxiliary shaft, and a releaser adapted to interrupt the function of the detent, the detent being controlled by the cam on the auxiliary shaft and the releaser by the cam on the main shaft, the first cam being operative before the second cam.

17. In a mechanism of the character described, comprising an oscillatory main shaft, a recessed cam mounted thereon, an oscillatory auxiliary shaft, a snail back cam mounted thereon, and a flexible connection between the shafts adapted normally to move the main shaft in unison with the auxiliary shaft when the latter is oscillated, a detent adapted to detain the auxiliary shaft and a releaser adapted to interrupt the function of the detent, the detent being controlled by the cam on the auxiliary shaft and the releaser by the cam on the main shaft.

18. In a mechanism of the character described, comprising an oscillatory main shaft, a cam mounted thereon, an oscillatory auxiliary shaft, a cam mounted thereon, and a flexible connection between the shafts adapted normally to move the main shaft in unison with the auxiliary shaft when the latter is oscillated, a detent adapted to detain the auxiliary shaft, and a releaser adapted to interrupt the function of the detent, the detent being controlled by the cam on the auxiliary shaft and the releaser by the cam on the main shaft, the detent and releaser being normally held against their respective cams by springs.

19. In a mechanism of the character described, comprising an oscillatory main shaft, a cam mounted thereon, an oscillatory auxiliary shaft, a cam mounted thereon, and a flexible connection between the shafts adapted normally to move the main shaft in unison with the auxiliary shaft when the latter is oscillated, a detent adapted to detain the auxiliary shaft and a releaser adapted to interrupt the function of the detent, the detent being controlled by the cam on the auxiliary shaft and a releaser by the cam on the main shaft, the detent and releaser being normally held against their respective cams by springs.
